Fig. 4.

Figure 1 is a side elevational view of a miniature railroad trestle structure, showing my new design;

Figure 2 is a top plan view of the structure illustrated in Figure 1;

Figure 3 is a front elevational view taken from the left-hand side of Figure 1 with the dotted line portion removed for convenience of illustration;

Figure 4 is a front elevational view taken from the righthand side of Figure 1 with the dotted line portion removed for convenience of illustration; and

Figure 5 is a fragmentary bottom plan view of the trestle structure shown in Figure 1 with the dotted line portion removed for convenience of illustration.

The dominant features of the design are shown in solid lines in the drawing.

I claim:

The ornamental design for miniature railroad trestle structure, as shown and described.
